UNITED STATES PATENT OFFICE

142,220

DESIGN FOR A BLOCK FOR USE IN APPLYING TIRE CHAINS

Paul C. Lyons, Union City, Pa.

Application April 16, 1945, Serial No. 119,021

Term of patent 14 years

(CL. D41—1)

To all whom it may concern:

Be it known that I, Paul C. Lyons, a citizen of the United States of America, residing at Union City, in the county of Erie and State of Pennsylvania, have invented a new, original, and ornamental Design for a Block for Use in Applying Tire Chains, of which the following is a specification, reference being had to the accompanying drawing, forming a part thereof.

In the drawing:

Figure 1 is a top plan view of my design for a block for use in applying tire chains,
Figure 2 is a side elevational view of the same,
Figure 3 is an end elevational view of the same.
I claim:

The ornamental design for a block for use in applying tire chains, as shown.

PAUL C. LYONS.
